S. P. COTTRELL

COMBINED LIGHT AND FIREARM

Filed July 11, 1925

UNITED STATES PATENT OFFICE.

SYLVESTER P. COTTRELL, OF BUFFALO, NEW YORK.

COMBINED LIGHT AND FIREARM.

Application filed July 11, 1925. Serial No. 42,991.

To all whom it may concern:

Be it known that I, SYLVESTER P. COTTRELL, a citizen of the United States, residing at Buffalo, in the county of Erie and 5 State of New York, have invented new and useful Improvements in Combined Lights and Firearms, of which the following is a specification.

This invention relates to a combined light 10 and firearm which may be used equally effective for lighting or shooting and its object is to provide a device of this character which is simpler, more effective and less expensive than those heretofore known. Generally speaking this improvement consists in so organizing the firearm portion of this device that the same can be built as a unit independently of the lighting portion of the same and then assembled with the latter 20 without one interfering with the other.

In the accompanying drawings:—

Figure 1 is a side elevation of my improved light and firearm.

Figure 2 is a front elevation of the same.

Figure 3 is a horizontal section taken on line 3—3, Fig. 1.

Figure 4 is a vertical longitudinal section of the same taken on line 4—4, Fig. 3, showing the parts of the firing mechanism in the 30 position which they occupy after the cartridge has been discharged and the pressure on the trigger has been released.

Figure 5 is a similar view showing the position of the parts when the firing hammer has been cocked.

Figure 6 is a view similar to Fig. 4 but showing the position of the firing mechanism after a cartridge has been fired and the pressure of the finger is still on the finger 40 piece of the trigger mechanism, this section being taken on line 6—6, Fig. 10.

Figure 7 is a fragmentary horizontal section taken on line 7—7, Fig. 9 and showing the switch mechanism for lighting and extinguishing the lamp.

Figures 8 and 9 are transverse sections taken on the correspondingly numbered lines in Fig. 4.

Figure 10 is a vertical transverse section taken on line 10—10, Fig. 6. 50

Figure 11 is a fragmentary vertical longitudinal section taken on line 11—11, in Figs. 8 and 12.

Figure 12 is a fragmentary vertical longitudinal section taken on line 12—12, 55 Fig. 11.

Similar characters of reference indicate like parts throughout the several views.

The lamp or lighting portion of this device comprises a tubular casing 20 which is 60 provided at its front end with a lens 21 through which the light of the lamp 22 shines upon closing a switch 23 which is in circuit with this lamp and a dry battery 24 mounted in the rear part of the casing. The 65 details of this lighting device may be of any suitable and well known construction and a further description of the same is, therefore deemed unnecessary.

At a point between the lamp and battery 70 the top and bottom of the casing is provided with a top opening 25 and a bottom opening 26 which are arranged vertically in line with each other. Projecting downwardly through the top opening 25 and ar-

anged with its lower part within the casing and with its upper part above the casing is a frame 27 which forms a part of the firing mechanism and supports the working 75 parts thereof. This frame is provided with a gun barrel 28 which projects forwardly from the upper part of the frame over the adjacent part of the lamp casing and practically terminates flush with the front end of the latter.

Projecting rearwardly from the upper part of the gun frame and over the adjacent part of the casing is a hood 29 the rear end of which receives a fastening screw 30 whereby the gun frame together with the parts mounted thereon are detachably 80 secured to the lamp casing, as best shown in Figs. 4 and 5.

Within the upper part of the frame is mounted a cartridge cylinder 31 which is 85 pivotally mounted on this frame by means of a horizontal longitudinal pin 32 so that

the cartridge receiving chambers 33 of this cylinder may be successively brought into register with the rear end of the gun barrel.

- 5 The numeral 34 represents a firing hammer which is pivoted at its lower end on the lower rear part of the frame by means of a horizontal transverse pin 35 and provided at its upper end with a firing pin 36 adapted 10 to strike the rear end of the cartridge 37 in the respective chamber of the cylinder which is in line with the gun barrel. This hammer has its upper end arranged within the hood 29 of the frame and is constantly 15 covered thereby during its forward and backward movement so that no separate cover or closure for protecting this hammer is necessary and thus simplifies the construction and cost of the device.
- 20 This hammer when free is thrown forwardly for firing a cartridge by means of a main spring 38 which is of leaf form and arranged on one side of the hammer and secured at its upper end by means of a screw 25 39 or otherwise to the adjacent rear part of the gun frame and provided at its lower end with a laterally and inwardly projecting finger 40 which presses rearwardly against the front side of a lip 41 projecting down- 30 wardly from the lower part of the hammer, as best shown in Figs. 4-6, 9 and 11.

A trigger mechanism is provided which operates to first retract or move the hammer rearwardly and then release the same so that 35 it will fly forwardly under the action of the spring 38 and discharge the cartridge. In its preferred form this trigger mechanism is constructed as follows:—

- 40 The numeral 42 represents the upper part or body of the trigger which is pivotally connected at its front end by means of a horizontal transverse pin 43 with the adjacent lower part of the gun frame, and 44 is the lower part or finger piece of the trigger which is pivotally connected at its upper end with the body 42 by means of a horizontal transverse pin 45. When in its operative position the finger piece 44 projects downwardly through the bottom opening 45 26 of the casing, as shown by full lines in Figs. 1, 4, 5, 6, and 8-10, but when the device is not in use this finger piece may be swung forwardly and upwardly so that it lies close to the under side of the casing, as 55 shown by dotted lines in Fig. 1, and thereby renders the same more compact for convenience in carrying in the pocket or storing the same away. The backward movement of the finger piece relative to the body of the 60 trigger is limited so as to render the same practically rigid relatively to each other at this time by cooperating stop surfaces 46 47 arranged on these parts, as shown in Fig. 6. The retracting movement of the trigger 65 is effected by a spring device which prefer-

ably consists of a plunger 48 guided in a heel 49 on the front part of the trigger body, and bearing against the adjacent part of the main frame and a spring 50 mounted in a pocket on this heel and bearing against the rear or inner end of this plunger, as 70 shown in Fig. 5. Motion is transmitted from the trigger to the hammer by means of a sear 51 which is pivotally connected at its lower end with the trigger by mounting it 75 on the same pin 45 which pivotally connects the body and finger piece of the trigger, as shown in Figs. 4, 5 and 6. While the upper end of this sear is adapted to engage with a nose 52 on the lower front part of the hammer, as shown in Figs. 4, 5 and 11 this sear is yieldingly held in its rearward operative position by a spring device which preferably consists of a plunger 53 guided in a pocket on the trigger body bearing 80 against the front side of the sear and a spring 54 arranged in said pocket and bearing against the inner end of the plunger 53, as shown in Figs. 4 and 5. In the fully retracted position of the trigger and while 85 the hammer is in its foremost position the sear is arranged with its upper or free end immediately below the nose of the hammer, as shown in Fig. 4. Upon now drawing the finger piece backwardly this sear by pushing 90 upwardly against the nose 52 will cause the hammer to be retracted and move its firing pin 36 backwardly away from the cartridge 37. This movement continues until the 95 breast on the rear side of the sear by engaging the lower front part of the hammer pries the sear away from the hammer and causes the front end of the sear to slip forwardly off from the nose 52 of the hammer, thereby releasing the latter and permitting 100 the main spring to throw it forwardly for engaging the firing pin with the cartridge. In Fig. 5 the sear is represented in a position in which it has moved the hammer into this rearmost position and is about to clear 105 the nose 52 of the hammer, while in Fig. 6 the trigger is shown in its fully raised position in which the sear is disengaged from the hammer nose 52 and the hammer has been thrown forwardly by its main spring. After the trigger has cleared the hammer it 110 continues its upward movement until the free end of the sear strikes the under side of the cartridge cylinder, as shown in Fig. 6, thereby not only limiting the upward movement of the trigger but also causing the sear to hold the cartridge cylinder reliably against displacement so that the cartridge which for the time being is in line with the gun barrel will be hit by the firing pin during the subsequent firing stroke of the hammer. During the downward or re- 115 tracting movement of the trigger the sear will simply trip idly past the hammer nose 52 and assume a position underneath the 120 125 130

latter preparatory to effecting the next firing operation:

The forward rotation of the cartridge cylinder is effected by means of a feed pawl 55 which is pivotally mounted at its lower end on the hammer in front of the axis 35 of the latter while the upper end or jaw of this pawl is adapted to engage successively with ratchet teeth 56 arranged in an annular row on the rear end of the cartridge cylinder about the axis of the same. During each forward or firing stroke of the hammer the feed pawl 55 is drawn downwardly idly preparatory to engaging the next cylinder ratch tooth 56 and during the retracting or backward stroke of the hammer this pawl by engaging the ratchet tooth 56 turns the cylinder forwardly one step for bringing the next cartridge cylinder in line with the gun barrel 28. The feed pawl is yieldingly held in its forward or operative position in engagement with the ratchet teeth by means of a spring device which co-operates with the pivot of the feed pawl and in the preferred form of this pivot and spring device the same, as best shown in Figs. 11 and 12 are constructed as follows:

The numeral 57 represents a pivot pin which projects laterally from the lower end of the feed pawl 55 and turns in a bearing 58 in the lower front part of the hammer and is provided on its upper side with an inclined bearing face 59. The numeral 64 represents a tension spring arranged in a pocket 61 on the lower front part of the hammer and bearing at its lower end against the inclined face 59 on the pivot pin 57 while its upper end bears against a screw plug 60 which is secured in the upper end of the pocket 61. Due to the constant pressure of the spring 64 against the inclined surface 59 on the pivot pin the feed pawl 55 is yieldingly pressed forwardly so that its feed jaw or beak will remain constantly in yielding engagement with the ratchet teeth 56, and therefore insures proper advancement of the cartridge cylinder during each operation of the gun.

On its upper rear part the feed pawl is provided with a retaining finger 63 which is adapted to engage with the rear side of the gun frame when the cartridge cylinder is removed from the frame for cleaning or repairing, and thereby prevents the feed pawl from moving forwardly into a position which would render it difficult to reassemble the parts.

In order to prevent the cartridge cylinder from being moved to an excessive extent during each forward throw under the action of the feed pawl and to thus insure proper alignment of each cartridge chamber with the gun barrel and hammer at the end of each firing operation a frictional detent device is provided which in the preferred

construction consists of a leaf spring 62 secured at its lower end to the main frame and bearing with its upper end against the periphery of the cartridge cylinder, as shown in Fig. 10.

In addition to securing the body or frame 27 to the top of the casing 20 by means of the screw 30 additional fastening means may be employed such as the screws 67 which connect the lower parts of the body 75 and casing, as shown in Figs. 1, 9 and 10. Upon removing the screws 30, 67, the body with the firing mechanism mounted thereon may be removed upwardly from the casing as a completely assembled unit, thereby not only facilitating manufacture but also permitting inspection, adjustment and repairing of the firing mechanism.

As a whole this firearm and lighting device is comparatively simple and compact in construction, it is well protected and not liable to get out of order, and in the event that inspection for repairing or adjusting any of the parts becomes necessary this can be accomplished easily and conveniently 90 without dismembering the entire mechanism.

I claim as my invention:—

1. A combined light and fire arm, comprising a tubular casing having openings in its top and bottom, a frame extending from the upper side of said casing downwardly through said top opening and provided on its front side with a barrel which projects forwardly over the casing and on its rear side with a hood projecting rearwardly over said casing, a cartridge cylinder pivotally mounted in said frame and provided with an annular row of chambers adapted to receive cartridges and to be brought successively in line with said barrel, a hammer pivoted on the rear part of the frame and provided with a firing pin adapted to strike the cartridge in the respective chamber which is in line with said barrel and having its upper end 100 covered by said hood, and a hammer operating mechanism mounted on the lower part of said frame and having a finger piece adapted to project downwardly through said bottom opening.

2. A combined light and firearm, comprising a tubular casing having openings in its top and bottom, a frame extending from the upper side of said casing downwardly through said top opening and provided on its front side with a barrel which projects forwardly over the casing, a cartridge cylinder pivotally mounted in said frame, and provided with an annular row of chambers adapted to receive cartridges and to be brought successively in line with said barrel, a hammer pivoted on the rear part of the frame and provided with a firing pin adapted to strike the cartridge in the respective chamber which is in line with said bar- 125 130

rel, and a hammer operating mechanism mounted on the lower part of said frame and having a finger piece adapted to project downwardly through said bottom opening.

- 5 3. A combined light and firearm, comprising a tubular casing having openings in its top and bottom, a frame projecting from the upper side of said casing downwardly through the top opening thereof, a cylinder 10 pivotally mounted in the frame and provided with an annular row of cartridge chambers, a hammer arranged in rear of said frame and provided at its upper end with a firing pin adapted to strike the cartridges in 15 said chambers and having its lower end pivoted on said frame and provided with a downwardly projecting lip, a flat main spring arranged in rear of the frame and having its upper end secured thereto and its 20 lower end provided with a laterally projecting finger engaging with the front side of said lip, and an operating mechanism for said hammer having a finger piece adapted to project downwardly through said bottom 25 opening.

4. A combined light and firearm, comprising a tubular casing having openings in its top and bottom, a frame projecting from the upper side of said casing downwardly 30 through the top opening thereof, a cylinder pivotally mounted in the frame and provided with an annular row of cartridge chambers, a hammer arranged in rear of said frame and provided at its upper end with a 35 firing pin adapted to strike the cartridges in said chambers and having its lower end pivoted on said frame and provided with a forwardly projecting toe, a main spring mounted on the frame and engaging the hammer 40 for throwing the same forwardly, a trigger pivoted on the lower part of the frame and having a finger piece adapted to project downwardly through said bottom opening, and a sear pivoted on said trigger and adapted 45 to engage said toe.

5. A combined light and firearm, comprising a tubular casing having openings in its top and bottom, a frame projecting from the upper side of said casing downwardly 50 through the top opening thereof, a cylinder pivotally mounted in the frame and provided with an annular row of cartridge chambers, a hammer arranged in rear of said frame and provided at its upper end 55 with a firing pin adapted to strike the cartridges in said chambers and having its lower end pivoted on said frame and provided with a forwardly projecting toe, a main spring mounted on the frame and engaging 60 the hammer for throwing the same forwardly, a trigger pivoted on the lower part of the frame and having a finger piece adapted to project downwardly through said bottom opening, and a sear pivoted on said 65 trigger and adapted to engage successively

with said toe for retracting the hammer and the periphery of said cylinder for arresting rotation thereof.

6. A combined light and firearm, comprising a tubular casing having openings in its top and bottom, a frame projecting from the upper side of said casing downwardly through the top opening thereof, a cylinder pivotally mounted in the frame and provided with an annular row of cartridge 70 chambers, a hammer arranged in rear of said frame and provided at its upper end with a firing pin adapted to strike the cartridges in said chambers and having its lower end pivoted on said frame and provided with a forwardly projecting toe, a main spring mounted on the frame and engaging the hammer for throwing the same forwardly, a trigger having a body pivoted on the frame and provided with a forwardly projecting heel and a finger piece pivoted on the rear part of the trigger body and capable of swinging forwardly therefrom through said bottom opening but limited 80 in its backward movement relatively thereto, a spring means interposed between the heel of said body and the frame for retracting the trigger, a sear pivoted on the trigger and adapted to engage said toe for retracting the hammer, and spring means interposed between the trigger and sear for holding the latter yieldingly in its operative position. 90

7. A combined light and firearm, comprising a tubular casing provided with top and bottom openings, a frame projecting downwardly through said top opening into said casing, a cylinder pivotally mounted on said frame and provided with cartridge chambers, a hammer pivoted on the frame and having a firing pin adapted to strike the cartridges in said chamber, and a leaf detent spring mounted at one end on said frame and engaging its other end with the periphery of said cylinder. 100

8. A light and firearm, comprising a tubular casing having top and bottom openings, a frame arranged within the casing, a cartridge cylinder pivotally mounted on the frame and projecting upwardly through said top opening and having an annular row of ratchet teeth on its rear end, a hammer pivoted on the rear part of said frame and provided with a firing pin adapted to strike the cartridges in said cylinder, a trigger mechanism for operating said hammer and having a finger piece adapted to project through said bottom opening, and a feed pawl pivoted on said hammer and having a jaw engaging said ratchet teeth and also having a retaining finger adapted to engage with the adjacent part of said frame. 115

9. A light and firearm, comprising a tubular casing having top and bottom openings, a frame arranged within the casing, a 120

cartridge cylinder pivotally mounted on the frame and projecting upwardly through said top opening and having an annular row of ratchet teeth on its rear end, a hammer pivoted on the rear part of said frame and provided with a firing pin adapted to strike the cartridges in said cylinder, a trigger mechanism for operating said hammer and having a finger piece adapted to project

through said bottom opening, and means for 10 yieldingly holding said feed pawl in engagement with said ratchet teeth consisting of a pivot pin arranged on said pawl and turning in said hammer and provided with an inclined surface, and a spring mounted 15 on said hammer and bearing against said inclined surface.

SYLVESTER P. COTTRELL.
